United States Patent Office.

J. F. TALLANT, OF BURLINGTON, IOWA.

Letters Patent No. 97,832, dated December 14, 1869.

IMPROVED RAILWAY-RAIL.

The Schedule referred to in these Letters Patent and making part of the same.

To all whom it may concern:

Be it known that I, J. F. TALLANT, of Burlington, in the county of Des Moines, and State of Iowa, have invented a new and improved Railroad-Rail; and I do hereby declare that the following is a full, clear, and exact description thereof, reference being had to the accompanying drawings, making part of this specification, in which—

Figure 1 is a vertical transverse section through the base portion of the rail.

Figure 2 is a vertical transverse section through the two parts composing the rail.

Figure 3 is a top view of a section of rail, taken at a point where the ends of the two cap-pieces break joints with a base-piece.

Figure 4 is an elevation of the inner side of the rail, taken at a point where the ends of the two base-pieces break joints with a cap-piece.

Similar letters of reference indicate corresponding parts in the several figures.

To enable others skilled in the art to understand my invention, I will describe its construction and operation.

In the accompanying drawings—

A represents the cap or top section of the rail, and B is the bed or base section, upon which the cap is secured.

The cap A may be made of wrought-iron, or of steel, and it is preferably made of the well-known form of the upper portion of a solid T-shaped rail, so that the improved rails may be worked into a road with this form of rail.

The cap A is constructed by rolling-machinery, suitably adapted to the purpose, with a double-lipped head, a, a contracted neck, b, a hooked portion, c, and a downwardly and outwardly-inclined flat portion, d, the latter having an upwardly-curved toe, e, along its anterior edge.

Between the inferior end of the hooked lip c and the flattened surface of the portion d is a longitudinal concavity, which receives a corresponding longitudinal convex surface or ridge, h, which is the superior prominent portion of the rail-base B. Thus, it will be seen that the hooked lip c, which is on the inner side of the rail, when laid down, will have a firm bearing or seat, and will be sustained against lateral outward thrust.

From the rounded ridge h, the upper flat surface i of the base B is inclined outwardly to a longitudinal groove or concavity, j, which latter is terminated by a raised lip or ridge, f, and adapted to receive into it and afford a seat for the toe e of the flat portion or flange d of the cap A.

The bottom or inferior side of the base B is flat, and may be made of any required width, and the thin

lip f', forming the inner edge of this base, is adapted for receiving the heads of spikes, used in fastening the rails down to their cross-ties.

C C are holes, which are made vertically through the flanges d d of the caps A A, and through the outer lateral extensions of the rail-bases B B.

It will be seen, from the above description, that I arrange two bars of metal horizontally, one above the other, so as to form a co-continuous railway.

The base or lower bar is so shaped and placed that no direct blow from the wheels of a passing train can reach it.

The cap is so shaped as to work in with the common pattern of railway-iron, and to sit astride of said base, it being firmly bolted to the base, so as to break joints, and form a continuous rail, which may be used with the common wooden ties and square spikes, or bolts may be passed through both of said upper bars, and also through a wrought-iron sleeper or tie, invented by me expressly for the purpose. In this way, I form a permanent railway-track, which cannot get out of order, or work loose, so long as the metal of which it is composed retains its integrity.

The cap or upper bars may be secured to their bases by means of slot-bolts, fastened under the rails or ties, as the case may be, by screw-bolts, each one having an inclined head, adapted to fit the bar, only on one side, with a correspondingly-shaped slot in the cap-bar, so that when the latter requires repair or removal, a quarter turn or revolution of said bolt will loosen the cap, and allow it to be removed, and another substituted in its stead.

By making the cap B wedge-shaped, and using the largest end up, a large portion of the rail will not directly feel the weight and impetus or momentum of the trains, and that portion of the rail is not liable to break in any ordinary contingency.

The principle of this invention may also be applied to a rail which is rolled from a single bar of iron or steel. In that case, the cap or tread of the rail is not placed over the middle of the base, where it is usually located, but is drawn inward toward the centre of the track, so that its inner side is placed more nearly over the inner side of the base of the rail than its outer side is over the outer side of that base. The weight of the train of cars, in that case, operates directly and essentially to prevent the disturbance of the rail, by the outward thrust of the car-wheels.

In the compound rail, I regard the flat portion of the cap, which is represented in section, at d, as being of prime importance in the formation of the rail. But the hooked portion, shown in section at c, is not deemed indispensable, inasmuch as the downward pressure of the rolling stock will probably suffice to prevent any disturbance of the cap of the rail by any

lateral thrust. I, however, prefer the use of the hook *e* in all cases, by way of more abundant caution.

I am aware that many plans have heretofore been proposed for constructing a compound rail of two longitudinal parts, one of which shall comprise the base and the other the tread or cap of the rail, and having the parts so arranged as to break joints.

I do not, therefore, claim to have invented the construction of rails of that general description; but

What I do claim as new, and desire to secure by Letters Patent, is—

1. In the formation of such a rail, the construction of the cap *A* with an outer portion, *d*, extending to

near the extremity of the base *B*, where it abuts firmly against a shoulder, *e*, or its equivalent, substantially in the manner and for the purpose above shown.

2. In a compound rail, constructed as above described, the use of the hook-shaped wing *e*, to aid in resisting the outward thrust of the car-wheels, substantially in the manner above described.

J. F. TALLANT.
